UNITED STATES PATENT OFFICE

156,886

SEAT

Eugene Hoback, Los Angeles, Calif.

Application June 10, 1948, Serial No. 146,889

Term of patent 14 years

(Cl. D15—8)

To all whom it may concern:

Be it known that I, Eugene Hoback, a citizen of the United States, residing at Los Angeles, in the county of Los Angeles and State of California, have invented a new, original, and ornamental Design for a Seat, of which the following is a specification, reference being had to the accompanying drawing, forming part thereof.

Fig. 1 is a perspective view of the seat embodying my new design; Fig. 2 is a side elevational view thereof; and Fig. 3 is a rear elevational view of the same.

I claim:

The ornamental design for a seat, as shown.
EUGENE HOBACK.
